[57] CLAIM

The ornamental design for cheese, as shown and described.

DESCRIPTION

FIG. 1 is a perspective view of the cheese of the present invention having four generally rectangular and elongated cheese members disposed within a generally rectangular and elongated outer casing member, wherein in a preferred embodiment the outer casing member is generally dark in color, two of the cheese members are diametrically opposed to one another and generally dark in color, and two of the cheese members are diametrically opposed to one another and generally light in color;

FIG. 2 is cross-sectional view of the cheese in FIG. 1 wherein, by way of example, the outer casing member is generally black in color, the first pair of diametrically opposed cheese members are generally purple in color, and the second pair of diametrically opposed cheese members are generally yellow or gold in color;

FIG. 3 is cross-sectional view of the cheese in FIG. 1 wherein, by way of example, the outer casing member is generally red in color, the first pair of diametrically opposed cheese members are generally orange in color, and the second pair of diametrically opposed cheese members are generally white in color; and,

FIG. 4 is cross-sectional view of the cheese in FIG. 1 wherein, by way of example, the outer casing member is generally purple in color, the first pair of diametrically opposed cheese members are generally orange in color, and the second pair of diametrically opposed cheese members are generally red in color.

The characteristic feature of the foregoing design resides in providing a generally rectangular outer casing member having four generally rectangular and elongated cheese members disposed therein, wherein the outer casing member is generally dark in color, two of the cheese members are diametrically opposed to one another and generally dark in color, and two of the cheese members are diametrically opposed to one another and generally light in color.

FIG. 2

UNITED STATES PATENT AND TRADEMARK OFFICE
CERTIFICATE OF CORRECTION

PATENT NO. : Des. 408,614
DATED : April 27, 1999
INVENTOR(S) : Neil Bailey

It is certified that error appears in the above-identified patent and that said Letters Patent is hereby corrected as shown below: In the Drawing:

-- Figure 1 is a top perspective view of cheese showing our new design, the undisclosed bottom perspective view being a mirror image and the symbols represent the colors purple and yellow or gold;

Figure 2 is a cross-sectional view of a second embodiment of Figure 1, taken at any point along the rectangular casing, the only difference being the colors which are red (outer casing), orange and white; and

Figure 3 is a cross-sectional view of a third embodiment of Figure 1, taken at any point along the rectangular casing, the only difference being the colors which are purple (outer casing), orange and red. --

Signed and Sealed this

Twelfth Day of October, 1999
